(57) **CLAIM**

The ornamental design for a drawing tool as shown and described.

DESCRIPTION

FIG. 1 is a top front perspective view of a drawing tool according to a first embodiment hereof;

FIG. 2 is a bottom rear perspective view of the drawing tool of FIG. 1;

FIG. 3 is a left side view thereof of the drawing tool of FIG. 1;

FIG. 4 is a front view thereof of the drawing tool of FIG. 1; FIG. 5 is right side view thereof of the drawing tool of FIG. 1;

FIG. 6 is a rear view of the drawing tool of FIG. 1;

FIG. 7 is a top view of the drawing tool of FIG. 1;

FIG. 8 is a bottom view of the drawing tool of FIG. 1;

FIG. 9 is a top front perspective view of a drawing tool according to a second embodiment hereof;

FIG. 10 is a bottom rear perspective view of the drawing tool of FIG. 9;

FIG. 11 is a left side view thereof of the drawing tool of FIG. 9;

FIG. 12 is a front view thereof of the drawing tool of FIG. 9;

FIG. 13 is right side view thereof of the drawing tool of FIG. 9;

FIG. 14 is a rear view of the drawing tool of FIG. 9;

FIG. 15 is a top view of the drawing tool of FIG. 9;

FIG. 16 is a bottom view of the drawing tool of FIG. 9;

FIG. 17 is a top front perspective view of a drawing tool according to a third embodiment hereof;

FIG. 18 is a bottom rear perspective view of the drawing tool of FIG. 17;

FIG. 19 is a left side view thereof of the drawing tool of FIG. 17;

FIG. 20 is a front view thereof of the drawing tool of FIG. 17;

FIG. 21 is right side view thereof of the drawing tool of FIG. 17;

FIG. 22 is a rear view of the drawing tool of FIG. 17;

FIG. 23 is a top view of the drawing tool of FIG. 17;

FIG. 24 is a bottom view of the drawing tool of FIG. 17;

FIG. 25 is a top front perspective view of a drawing tool according to a fourth embodiment hereof;

FIG. 26 is a bottom rear perspective view of the drawing tool of FIG. 25;

FIG. 27 is a left side view thereof of the drawing tool of FIG. 25;

(Continued)

FIG. 28 is a front view thereof of the drawing tool of FIG. 25;
 FIG. 29 is right side view thereof of the drawing tool of FIG. 25;
 FIG. 30 is a rear view of the drawing tool of FIG. 25;
 FIG. 31 is a top view of the drawing tool of FIG. 25;
 FIG. 32 is a bottom view of the drawing tool of FIG. 25;
 FIG. 33 is a top front perspective view of a drawing tool according to a fifth embodiment hereof;
 FIG. 34 is a bottom rear perspective view of the drawing tool of FIG. 33;
 FIG. 35 is a left side view thereof of the drawing tool of FIG. 33;
 FIG. 36 is a front view thereof of the drawing tool of FIG. 33;
 FIG. 37 is right side view thereof of the drawing tool of FIG. 33;
 FIG. 38 is a rear view of the drawing tool of FIG. 33;
 FIG. 39 is a top view of the drawing tool of FIG. 33;
 FIG. 40 is a bottom view of the drawing tool of FIG. 33;
 FIG. 41 is a top front perspective view of a drawing tool according to a sixth embodiment hereof;
 FIG. 42 is a bottom rear perspective view of the drawing tool of FIG. 41;
 FIG. 43 is a left side view thereof of the drawing tool of FIG. 41;
 FIG. 44 is a front view thereof of the drawing tool of FIG. 41;
 FIG. 45 is right side view thereof of the drawing tool of FIG. 41;
 FIG. 46 is a rear view of the drawing tool of FIG. 41;
 FIG. 47 is a top view of the drawing tool of FIG. 41;
 FIG. 48 is a bottom view of the drawing tool of FIG. 41;
 FIG. 49 is a top front perspective view of a drawing tool according to a seventh embodiment hereof;
 FIG. 50 is a bottom rear perspective view of the drawing tool of FIG. 49;

FIG. 51 is a left side view thereof of the drawing tool of FIG. 49;
 FIG. 52 is a front view thereof of the drawing tool of FIG. 49;
 FIG. 53 is right side view thereof of the drawing tool of FIG. 49;
 FIG. 54 is a rear view of the drawing tool of FIG. 49;
 FIG. 55 is a top view of the drawing tool of FIG. 49; and,
 FIG. 56 is a bottom view of the drawing tool of FIG. 49. The broken lines in the figures show portions of the drawing tool that form no part of the claimed design.
